VACUUM CLEANER

Gustaf Einar Lofgren, Riverside, and Charles L. Brown, Jr., Stamford, Conn., assignors to Electrolux Corporation, Dover, Del., a corporation of Delaware

Application May 12, 1938, Serial No. 207,532

6 Claims. (Cl. 220—73)

This invention relates to vacuum cleaners and more particularly to vacuum cleaners of the so-called inside bag type.

In the operation of household appliances, such as vacuum cleaners, it sometimes becomes desirable to partially disassemble the machine for inspection or repair. However, external securing means for the parts of a vacuum cleaner which are exposed for ready access may scratch or mar furniture as it is pulled around the floor.

In accordance with this invention the parts of the vacuum cleaner are nested together and the securing means covered to present a smooth exterior. The securing means are made accessible by the arrangement of the parts of the machine.

What is considered to be novel and invention may be better understood by reference to the following specification and appended claims when considered in connection with the accompanying drawings, in which

Fig. 1 is a side view of our improved vacuum cleaner broken away in part;

Fig. 2 is a side view of the upper shell of the casing;

Fig. 3 is an end view of the upper shell;

Fig. 4 is a side view of the lower shell of the casing;

Fig. 5 is a sectional view taken along the line 30 5—5 of Fig. 4;

Fig. 6 is a side view of the two shells secured together.

Fig. 7 is an end view of the two shells secured together;

Fig. 8 is a side view of the casing with brackets secured to it for holding parts to the exterior of the casing and with the bulkheads secured within the casing;

Fig. 9 is a sectional view taken along the line 40 9—9 of Fig. 8 showing the front bulkhead;

Fig. 10 is a sectional view taken along the line 10—10 of Fig. 8 showing the rear bulkhead;

Fig. 11 is a side view of the casing with the handle, end rings, and sleighs mounted on it;

Fig. 12 is a side view of a vacuum cleaner casing with the motor fan assembly and dust bag located in the casing;

Fig. 13 is an end view of the vacuum cleaner casing shown in Fig. 12; and

Fig. 14 is a perspective view of the completed assembly of the vacuum cleaner unit.

Referring particularly to Fig. 1 of the drawings, 10 indicates a vacuum cleaner to which a cleaning tool 11 is connected by means of a flexible hose 12 and a substantially rigid tubular

member 13. Mounted within the vacuum cleaner unit 10 is a motor 14 driving a multistage centrifugal fan 15 for producing a flow of air. A dust separating member 16 located within the vacuum cleaner unit 10 serves to separate from the air drawn in through the cleaning tool 11 the entrained dust. In the operation of the vacuum cleaner unit 10 it is necessary to remove the dust separating member 16 periodically to empty from it the dust collected therein. This 10 may be accomplished by removing the front end cover 17. Occasionally, it may be desirable to make a partial disassembly of the vacuum cleaner unit 10 for inspection or repair.

Vacuum cleaner unit 10 is provided with an 15 elongated casing 18 formed with an upper semi-cylindrical shell 19 and a lower shell 20 with substantially vertical side walls 21. Upper shell 19 has two flat side projections 22 extending substantially throughout the length of the shell. 20 Projections 22 are adjacent the edges of the shell 19 and serve to strengthen the side walls of the casing 18. Lower shell 20 is formed with inwardly extending ribs 23 to stiffen the bottom 24. The two shells 19 and 20 are formed in stamping operations with the projections 22 in shell 19 and the stiffening ribs 23 in the bottom of shell 20. The lower edges of shell 19 overlap the upper edges of the side walls 21 of shell 20. The side walls 21 abut shoulders 25 formed adjacent to the lower edges of shell 20 as best indicated in Fig. 7. The shells 19 and 20 may be secured together along the overlapping edges by spot or line welding.

A bracket 26 is secured to each side of the 35 casing 18 adjacent the front end, one of which is shown at the left in Fig. 8. Bracket 26 has two loops 27 which have horizontal axes. A similar bracket 28 is secured at each side of the casing 18 at the rear end shown at the right in 40 Fig. 8. Bracket 28 is also provided with two loops 29 having horizontal axes. An end view of the brackets 28 is shown in Fig. 10. U-shaped brackets 30 are secured to the side of the casing 18 between the ends of projections 22 and with 45 vertical axes. The brackets 26, 28, and 30 are preferably secured to the casing 18 by means of spot welding. A bracket 31 is secured to the top of the casing 18 and has two upstanding arms 32 with horizontal slots 33. Formed integrally with the bracket 31 is a retainer 34 for a square nut. In line with the bracket 31 and spaced longitudinally from it is a clip 35. Bracket 31 and clip 35 are secured to the casing 18 preferably by welding.

A bulkhead 36 in the form of a perforated plate is secured within the casing 18. A flange 37 is provided around the edge of the bulkhead 36 which may be secured to the casing 18 by means of welding. Bulkhead 36 performs two functions, first it separates the casing 18 into a dust separating chamber 38 and a fan motor chamber 39, second, it reenforces the casing 18. The perforations in the bulkhead 36 permit the air to pass from the dust separating chamber 38 to the fan motor chamber 39. When a cloth bag is used for the dust separating member 16, as best indicated in Fig. 1, the bulkhead 36 prevents the bag from being drawn over the opening into the fan 15 thereby preventing damage to the bag and insuring the utilization of the full area of the bag. For strengthening the bulkhead 36 radial ribs 40 are provided. A second bulkhead 41 is located within the casing 18 spaced a short distance from the rear end shown at the right in Fig. 8. Bulkhead 41 has a flange 42 by means of which it may be secured to the casing 18 preferably by welding. A central opening 43 is provided in the bulkhead 41. Three inwardly extending ears 44 are provided with apertures 45 to receive bolts for securing the motor 14 and fan 15 to the bulkhead 41. Bulkhead 41 serves to reenforce the casing 18 and to support the motor fan unit.

A bracket 46 shown in dotted lines in Fig. 8 is secured in the bottom of casing 18 adjacent the front end. The front end 47 of casing 18 is formed at an angle to the longitudinal axis of the casing. A front end ring 48 is secured to the front end 47 by means of bolts 49 which pass through the loops 27 of brackets 26. A bolt 50 passes through bracket 46 and is threaded into engagement with the bottom of front end ring 48. Front end ring 48 has an inwardly extending flange 51 forming a seat for a ring 52 carried by the dust separating member 16, as best indicated in Fig. 1. A rear end ring 53 is secured to casing 18 by means of bolts 54 which pass through the loops 29 in brackets 28. The top of rear end ring 53 is provided with journal extensions 55 which receive a pin 56 carried by handle 57. A pin 58 carried by the other end of handle 57 engages in slots 33 of bracket 31. For supporting the casing 18 on a horizontal surface, sleighs 59 are provided, only one of which is shown in Fig. 11. The ends of sleighs 59 enter openings provided therefor in the front end ring 48 and rear end ring 53. L-shaped clips 60 are secured to each end of sleighs 59 and extend over projections 61 (see Fig. 13) and are secured thereto by screws 62. Front end ring 48 is provided with two forwardly extending bosses 63 which are adapted to enter openings in the front end cover 17, as shown in Fig. 1, for securing the front end cover to the casing 18.

The fan 15 and motor 14 are secured together and inserted in the rear opening of casing 18. The fan motor assembly is secured to the bulkhead 41 by means of three bolts 64, shown in Fig. 13, which pass through the apertures 45 of ears 44. A portion of motor 14 extends outwardly of casing 18 with the motor brushes 65 located wholly without the casing 18 for convenience in examining and replacing the brushes. Two motor leads 66 are provided with spring clips 67 for detachable connection to a foot operated switch 68 shown in Figs. 1 and 14.

The securing means for the front end of handle 57 is covered by a handle cover 69 secured to the casing 18 by means of a screw 70 in threaded

engagement with the nut carried in retainer 34 and a strap 71 in engagement with clip 35. Screw 70 is covered by an overhanging lip 57a formed integrally with handle 57. The securing means for the front end ring 48 and the rear end ring 53 including the brackets 26 and 28 are covered by two plates 72, one of which is shown in Fig. 12. The plates 72 are secured to the casing 18 by means of two spring clips 73 which are inserted through openings in the edge of plates 72 into the vertical openings of the brackets 30. Rear end ring 53 is provided with two threaded apertures 74 located at opposite sides of the ring. A housing 75 carrying switch 68 and a switch cover 76 is secured to casing 18 by means of two screws 77 (see Fig. 1) which are in threaded engagement with the apertures 74. Switch cover plate 76 has two forwardly extending arms 78 which cover the sides of the journals 55 and pin 56 securing one end of the handle 57. When the front end cover 17 is secured to the casing 18, it encloses the forwardly extending bosses 63 by means of which it is secured to the casing.

The vacuum cleaner unit 10 may be assembled in the following sequence of operations:

The upper shell 19 and the lower shell 20 are placed in position with edges overlapping and the top edges of the sides 21 of shell 20 engaging the shoulders 25 of shell 19. The two shells are welded together along the overlapping edges. The brackets 30 with the vertical openings are secured to the casing 18 adjacent each end of the projections 22. The brackets 30 are preferably secured by spot welding. The perforated bulkhead 36 is secured within the casing by spot welding along the flange 37. The bulkhead 41 is positioned within the rear end of casing 18 and secured thereto, at least in part, by line welding along the flange 42. We have found it desirable to use line welding in securing the bulkhead 41 to the upper shell 19. However, due to the relatively irregular configuration of the shell 20, we have found it preferably to use spot welding along the side walls 21 and spot welding and soldering along the bottom 24. The brackets 26 and 28 are secured to the two sides of the casing adjacent the front and rear ends respectively. Brackets 26 and 28 may be secured by spot welding. Bracket 31 and clip 35 are secured to the top of the casing 18 by spot welding. Bracket 46 is secured within casing 18 by welding. The front end ring 48 is secured along the inclined front face 47 of the casing 18 by means of bolts 49 and 50. The rear end ring 53 is secured to the casing 18 by means of bolts 54. The sleighs 59 are secured to the front end ring 48 and the rear end ring 53 by inserting the free ends in the openings provided therefor and threading the screws 63 through the apertures provided in the clips 60. The handle 57 is secured to the journal extension 55 by pin 56 and to bracket 31 by pin 58.

The motor 14 and fan 15 are assembled together then secured within the casing 18 by bolts 64 passing through apertures 45 provided in ears 44 of bulkhead 41. The securing means for the front end of handle 57 is covered by handle cover 69. Handle cover 69 is secured to the casing 18 by engagement of transverse strap 71 with clip 35 and screw 70. Slide plates 72, for covering the securing means for the front end ring 48 and the rear end ring 53, are positioned over the securing means and the projections 22. The side plates 72 are then secured to the casing 18 by means of clips 73 inserted through the vertical openings of brackets 30. The rear end housing 75 together with switch 68 and switch cover plate 76

16 is secured to the casing 18 by means of screws 17. The switch cover plate 16 covers the securing means of the rear of handle 57. The dust separating member 16 is inserted in the dust separating compartment 38 and secured therein by front end cover 17. The assembly of the vacuum cleaner unit 10 is then completed.

If it is desired to partially or wholly disassemble the vacuum cleaner unit 10, it is simply necessary to remove the covering of the securing means to which access is desired. If it is desired to remove the front end ring 48 or the rear end ring 53, the side plates 72 are removed by removing the clips 73. Similarly, if it is desired to remove the handle 57, the handle cover 69 is removed by unscrewing the screws 70 and the rear end housing 75 is removed by unscrewing the screws 71. Access to the motor 14 may be obtained simply by removing the rear end housing 75, as pointed out above. By this arrangement, it is possible to remove any part of the vacuum cleaner unit 10 for inspection or repair and during operation the securing means for the various parts are covered and exposed 25 sharp corners and rough edges are completely eliminated.

What I claim is:

1. In a vacuum cleaner, a substantially cylindrical casing open at each end, two reinforcing rings extending around the exterior of said casing at each end, means for securing said rings to said casing located on opposite sides of said casing, and a plate detachably secured to each side of said casing for covering the securing 35 means for both of said rings.

2. In a vacuum cleaner, a substantially cylindrical casing open at each end, a plurality of brackets secured to the exterior of said casing at each end, reinforcing rings located at opposite ends of said casing, means securing said rings to said brackets, and detachable means covering said brackets and said securing means, whereby a smooth exterior is presented without

interference with ready assembly and disassembly of the cleaner.

3. In a vacuum cleaner, a substantially cylindrical two-part casing, means to secure said two parts together along horizontal lines, brackets secured to the sides of said casing at opposite ends, rings surrounding the two ends of said casing, means securing said rings to said side brackets, and means secured to said casing covering said brackets and said securing means, 10 whereby a smooth exterior is provided.

4. In a vacuum cleaner, a substantially cylindrical two-part casing, means to secure said two-parts together at opposite sides, projections from the sides of said casing for strengthening 15 the side walls of the casing, brackets secured to the opposite sides of said casing at each end, rings surrounding said casing at opposite ends, means to secure said rings to said brackets, and plates removably secured to said casing covering the joint of said bottom and top, said projections, said brackets, and said ring securing means whereby a smooth exterior is presented.

5. In a vacuum cleaner, a substantially cylindrical casing, brackets secured to the sides 25 of said casing at opposite ends, reinforcing rings extending around the opposite ends of said casing, means to secure said rings to said last-named brackets, and plates removably secured to the sides of said casing covering said brackets and 30 said ring securing means, whereby projecting parts secured to the exterior of said casing are covered to present a smooth exterior.

6. In a vacuum cleaner, a substantially cylindrical casing open at each end, a reinforcing ring extending around the exterior of said casing, means for securing said ring to said casing located on opposite sides of said casing, and a plate detachably secured to each side of said casing for covering the securing means for said 40 ring.

GUSTAF EINAR LOFGREN.
